UNITED STATES PATENT OFFICE.

HARRY F. HENLEY, OF RICHMOND, INDIANA.

TOY AEROPLANE.

1,299,465.

Specification of Letters Patent.

Patented Apr. 8, 1919.

Application filed December 7, 1918. Serial No. 265,697.

To all whom it may concern:

Be it known that I, HARRY F. HENLEY, a citizen of the United States, residing in the city of Richmond, in the county of Wayne, State of Indiana, have invented a new and novel Construction for Toy Aeroplanes, of which the following is a full, clear, and comprehensive specification and exposition, the same being such as will enable others to 10 make and use the same with exactitude.

The object of my present invention is to provide a toy aeroplane which will be attractive in appearance when in operation, adapted to give a maximum of amusement 15 in practice, which will simulate an actual power-driven aeroplane in flight, and which can be manufactured and sold at a comparatively low price.

Other minor objects and specific advantages will suggest themselves in the course of the following description, and that which is new will be correlated in the appended claims.

The aeroplane herein described is composed almost entirely of paper, or its equivalents, the various parts being cut to a specific pattern, then folded to the desired dimensions, with suitable braces, reinforcements, and securing means, whereby it will 30 retain its shape under comparatively severe usage.

The preferred means for carrying out the principles of my invention in a practical manner is shown in the accompanying drawings in which—Figure 1 is a plan view of the underside of the main portion of my invention, the tail being removed.

Fig. 2 is a top plan view of the invention complete, with the tail connected with the 40 main portion.

Fig. 3 is a front elevation of the invention.

Fig. 4 is a central longitudinal section as taken on the line 4—4 of Fig. 2. And Fig. 45 5 is a detail cross section, as taken on the line 5—5 of Fig. 4.

Similar indices denote like parts throughout the several views.

In order that the construction, the operation, and the advantages of my invention may be more fully understood and appreciated, I will now take up a detailed description thereof, in which I will set forth the invention as fully and as comprehensively as I may.

In the drawings numeral 1 denotes the

body or main portion of the fuselage, the same being V-shaped in cross section, from the upper edges of which project the laterally extending reinforcements 2 and 3 integral therewith. Numerals 4 and 5 denote the two planes or wings, whose inner central portions rest on the reinforcements 2 and 3, with their inner edge portions turned downward into the fuselage member 1 but not attached thereto. A flange 6 is formed along the central portion of the forward edges of the wings 4 and 5, which flange is turned back and secured to the under sides of the wings, and to the reinforcements 2 and 3. A bamboo or other stiffening strip 7 is inclosed by said flange 6.

Clips 8 and 9 are located near the middle of the strip 7, and they clamp the flange 6 against the members 2 and 3 and the wings 75 4 and 5, and they also contribute to retaining the strip 7 in place.

Numerical 10 denotes the stem-post, or plate, which may be formed of a plurality of thicknesses of paper or card-board, the 80 same being located between the forward parts of the down-turned parts of the wings which extend into the fuselage member 1. The forward edge of said stem-plate is located even with the forward edges of the 85 wings, projecting to a point at the top, from which it curves rearward and downward. The metal clips 11 and 12 clamp the forward edges of the fuselage member 1 upon the stem-plate and retain these parts together, 90 and they also act as the prow or air divider which divides the air in flight, and they also act as balancing weights for the device.

Numerical 13 denotes the upper guy wire or cord, which is disposed through an aperture, at *a*, in the stem 10, with its ends secured to the wings by the clips 8 and 9, whereby the wings are supported at the desired angle.

Numerical 14 denotes the lower guy wire or 100 cord, which is disposed under the forward portion of the fuselage member 1, with its ends secured by the clips 8 and 9, whereby the wings are prevented from folding upward beyond a predetermined degree to 105 which they are adjusted.

Immediately to the rear of the clips 11 and 12 there is a detachable reinforcing pad 15, whose center contacts with the lower edge of the fuselage, with its sides bent upwardly into contact with the sides of the fuselage, and extending to the inner edges

of the reinforcements 2 and 3. A cotter or other pin 16 passes horizontally through the two sides of the pad 15, through the fuselage, and through the stem 10, to hold 5 said parts together and to form attaching means for the truck hereinafter described.

The truck comprises an axle 17 having the ground wheels 18 and 19 mounted on each end thereof. Connected with the axle 10 17 are the two arms or hounds 20 and 21 which project upward convergently from near the wheels 18 and 19 and integrally connected at their upper ends with the upper ends of the loop 22, which latter is doubled 15 around the pad 15, fitting snugly thereagainst.

The upper ends of the hounds 20 and 21, and of the loop 22, are secured in place by the pin 16, from which it is evident that 20 the loop 22 will prevent the truck from swinging forward or backward.

In order that the truck may be moved forward or backward from the position in which it is shown I have provided additional apertures, *b* and *d*, formed through 25 the fuselage and the stem plate into which said pin 16 may be inserted when the truck is moved forward or rearward, to enable one to properly balance the device under various 30 conditions.

Numerals 23 denotes an image of a pilot or ace, the lower portion of which is secured to the interior of the fuselage.

Numeral 24 denotes the tail member of 35 the fuselage, the same being V-shaped in cross section, its forward pointed end portion being adapted to be inserted into the member 1 of the fuselage, where it is retained by the inner end portions of the 40 wings which fit into the member 1, whereby a channel is formed for the member 24, which is slidably retained in place by the compression.

The tail plane comprises two integral 45 members 25 and 26 having its center formed V-shaped to fit in the V-shaped member 24, across which it extends horizontally, and to which it is secured.

The forward edge of the tail plane is 50 turned back forming the flange 30, which is secured over the stiffening reed or wire 27, to retain the members 24 and 25 in proper extended position.

Extending upwardly and divergently 55 from the central V-shaped portion of the members 25 and 26, are the stabilizing fins 28 and 29, which are secured to the sides of said V-shaped portion.

One of the distinctive features of this invention resides in the fact that the rear 60 inner corners of the wings 4 and 5, that is at the points *x* and *z*, are capable of being sprung toward each other, whereby in the event that the device strikes an object on 65 either side of the stem 10 then the shock will

be absorbed, as the rear edges of the wings will simply spring toward each other and then rebound to their normal positions, thereby preventing damage to the device even under severe usage.

Another important feature is that of the two-part telescopic fuselage, by which the tail plane may be adjusted forward and backward with relation to the wings 4 and 5, thereby adapting the device to variations in 70 maneuvers. A further feature resides in the ability to adjust the truck forward or backward, and the ease with which the truck may be removed for certain maneuvers.

And still another important feature resides in the novel manner of retaining the wings 4 and 5 at their proper radial angle, which is accomplished by means of the guys 13 and 14, which prevent the wings from collapsing or folding up or down.

To operate the device one has only to grasp the fuselage in the rear of the truck with a thumb and finger and then throw the device forward and upward into the air. This will cause the device to sail forward, 90 transacting various evolutions, such as quick turns, nose-dives, loop-the-loops, upward glides, and downward slides, and frequently boomeranging back to the thrower.

Having now fully shown and described 95 my invention, what I claim and desire to secure by Letters Patent of the United States, is—

1. A toy aeroplane comprising a two-part telescoping fuselage, a pair of wings extending out laterally from the sides of the front member of the fuselage, a stem-plate located between the sides of the forward end of the fuselage, an upper guy preventing the wings from turning downward, a lower guy preventing the wings from turning upward, a tail plane carried by the rear member of the fuselage, and fins extending divergently 105 from above the tail plane.

2. A toy aeroplane comprising a two-part fuselage which is V-shape in cross section, the rear member of the fuselage being adapted to telescope into the forward member of the fuselage, reinforcements extending out from the upper edges of the body member, 110 wings contacting with said reinforcements with their inner edges projecting into the body member, stiffening means connecting said wings, a stem-plate extending up from between the sides of the forward member of the fuselage, a truck detachably and adjustably attached to the forward portion of the body member, guys for retaining the wings in normal position, and tail planes secured to the rear end of the rear member of the 120 fuselage.

3. A toy aeroplane composed principally of paper, comprising the main body member of the fuselage, wings extending out from said body, reinforcements extending out 125

- from the body member and secured to the wings, a stem-plate located between the members of the body member, clips clamping the forward edges of said body upon the 5 inner ends of the wings and the stem-post, guys retaining the wings in proper position, means for stiffening the forward edges of the wings, the rear inner corners of the wings being adapted to spring toward each other, 10 a rear member of the fuselage adapted to telescope into the body member and in contact with the inner ends of the wings, tail planes extending out from the rear member of the fuselage, means for stiffening the 15 forward edges of the tail planes, and stabilizing fins flaring upward from the rear portion of the rear member of the fuselage.
4. A toy aeroplane composed of sheets of paper cut to proper contour with certain of 20 parts pasted together and including a tapering V-shaped body member, reinforcements extending out from the upper edges of the body member, wings secured to said reinforcements with their inner ends extending 25 down into said body member, a tail member having its forward portion slidably located in the body member and between it and the ends of said wings, a vertical stem located between the members of the forward portion 30 of the body member, clips retaining the forward edges of the body member the forward inner corners of the wings and the stem in contact with each other, an image extending
- upward from the rear portion of the body member, tail planes extending out from the 35 rear ends of the tail member, and fins extending up from midway of said tail planes.
5. A toy aeroplane formed of paper, comprising an elongated body V-shaped in cross section, reinforcements extending out from 40 the upper edges of the body, comparatively large wings having their inner portions resting on said reinforcements with their inner ends located loosely in said body, stiffening for the forward edges of the wings, a stem 45 extending up from the forward end of the body, guys extending through the upper portion of the stem and underneath the body member with their ends secured to the forward edges of the wings to retain the wings 50 at the desired angle, a truck detachably and adjustably attached to the forward portion of the body member, means for preventing the truck from turning forward or backward, an adjustable tail member telescopically inserted into the body member, and tail planes secured to the rear end of the tail member. 55

In testimony whereof I have hereunto subscribed my name to this specification in the 60 presence of two subscribing witnesses.
